(21) Appl. No.: **29/226,920**

(57) **CLAIM**

(22) Filed: **Apr. 4, 2005**

The ornamental design for an indexable insert milling cutter
having an integral ER shank, as shown and described.

(51) LOC (8) Cl. **15-09**

DESCRIPTION

(52) U.S. Cl. **D15/139**

FIG. 1 is a perspective view of an indexable insert milling
cutter having an integral ER shank showing my new design.

(58) Field of Classification Search D15/139,
D15/127; 407/113–116, 34, 35, 53, 54, 42,
407/63, 64, 65

FIG. 2 is a front elevational view thereof,

See application file for complete search history.

FIG. 3 is a rear elevational view thereof,

FIG. 4 is a right side elevational view thereof,

FIG. 5 is a left side elevational view thereof,

FIG. 6 is a top plan view thereof; and,

FIG. 7 is a bottom plan view thereof.
